UNITED STATES PATENT OFFICE

152,414

DESIGN FOR A PHONOGRAPH TONE ARM OR THE LIKE

Joseph B. Federico, New Baltimore, Mich., assignor to The Astatic Corporation, Conneaut, Ohio, a corporation of Ohio

Application August 29, 1947, Serial No. 141,123

Term of patent 7 years

(Cl. D26—14)

To all whom it may concern:

Be it known that I, Joseph B. Federico, a citizen of the United States, residing at New Baltimore, in the county of Macomb and State of Michigan, have invented a new, original, and ornamental Design for Phonograph Tone Arm or the like, of which the following is a specification, reference being had to the accompanying drawing, forming part thereof.

Figure 1 is a perspective view of a phonograph tone arm or the like, embodying my novel design.

Figure 2 is a side elevation of the rear portion of the phonograph tone arm of Figure 1 looking in the direction of the arrow, II.

Figure 3 is a section taken at line III—III of Figure 1.

Figure 4 is a section taken at line IV—IV of Figure 1.

Figure 5 is a side elevation of the forward portion of the phonograph tone arm of Figure 1 and is taken in the direction of the arrow V.

I claim:

The ornamental design for a phonograph tone arm or the like, as shown.

JOSEPH B. FEDERICO.
